GARMENT PRESSING MACHINE

William Strobridge, Syracuse, N. Y., assignor to
 United States Hoffman Machinery Corporation,
 New York, N. Y., a corporation of Delaware

Application October 16, 1939, Serial No. 299,773

8 Claims. (Cl. 38—15)

This invention relates to garment pressing machines and more particularly to means for controlling the steam spray to the pressing elements of such machines.

In the prior art it has been proposed to provide the pressing elements of a garment pressing machine with means for supplying steam to the steam chambers of the movable pressing element or head, and to the fixed pressing element or buck. In such arrangements the control means have been duplicated for the two elements. All such known arrangements of the prior art have required numerous operating parts and have been particularly objectionable not only because of the large number of control elements required, but also because they do not leave both of the operator's hands free to position the garments being steamed. The present arrangement is designed to overcome the disadvantages pointed out above and to otherwise improve and simplify steam spray control for garment pressing machines.

The main object of the present invention is to simplify and unify the mechanism for the control of the steam spray of pressing machines and to leave both hands of the operator free during a steaming operation. Another object is to arrange the parts so that one mechanism may be employed to apply steam to either of the pressing elements under the selective control of the operator.

Other objects of the invention will appear from the following description when it is read in connection with the accompanying drawings, in which—

Fig. 1 is a side view partly in section of a garment pressing machine having one form of steam spray control mechanism embodying the present invention;

Fig. 2 is a detail view showing the selecting mechanism of the present invention;

Fig. 3 is a sectional view on line III—III of Fig. 2;

Fig. 4 is a detail view of a portion of the steam valve controlling mechanism associated with the fixed pressing member or buck of the machine;

Fig. 5 is a side view similar to Fig. 1, but showing a modified form of steam spray control mechanism; and

Fig. 6 is a detail view of one form of steam valve suitable for use on the movable pressing element of the machine.

In the drawings, reference character 11 designates generally the frame of a garment pressing machine having a forward upstanding portion 55

12 carrying a fixed pressing element or buck 13, and a rear upstanding portion 14 about which the head carrying lever 15 is pivoted at 16. The lever 15 carries the usual movable pressing element or head 17 cooperating with the buck 13 and having the usual counter-balancing weight 18. Inasmuch as these parts are conventional and the invention is concerned not with the structural elements of the machine but with the steam spray mechanism, it will be sufficient for the purposes of the present invention to describe these parts briefly. The movable head 17 is operated by two sets of toggles designated 21 and 22 under the control of a foot pedal 23. Spring 19 tends to lift the head to open the press. As shown, the mechanism includes a buffer 24 against which toggle 21 strikes in its straightened or press closing position, and a spring 25 for assisting in the opening of the press when the toggle 22 is broken. Fulcrum 26 of toggle 22 is carried on the frame of the machine in any convenient manner.

The head 17 is also assisted in its opening movement by the counter-weight 18 and spring 19, and is closed by manipulation of foot pedal 23 and operating handle 27. The pressing elements 13 and 17 may embody any usual construction which includes hollow steam heating chambers with perforated faces which usually

30 carry padding contacting with the garments to be pressed. In such machines it has been found desirable and beneficial to at times spray steam from the steam chambers in the elements to the garment contacting portions of the elements.

35 This steam assists in the shaping and pressing operation as well as tending to raise the nap on the cloth. The present invention is concerned with the utilization of a single mechanism providing for manual selection of the spray of steam from the head or from the buck, that is, means are provided under the convenient control of the operator for spraying steam from either the head or the buck at will, through a single operating mechanism with interposed manual selecting means.

In Fig. 1 and by way of illustration the buck 13 is shown as having a source of steam supply 28 for delivering steam to its steam heating chamber, whence it can be directed outwardly from the buck onto the garment by the opening of a steam control valve 29 having an operating rod 30. Similarly, the head 17 has a steam connection 32 for supplying steam to its steam heating chamber whence it may be directed outwardly from the head under the control of a valve 33.

shown in detail in Fig. 6. The valves 29 and 33 may be of any suitable type such as that disclosed and claimed in the application of Clarence M. Clarke, Serial No. 208,688, filed May 18, 1938, to which reference may be had for details.

For purposes of the present description it will be sufficient to say that when these valves are of the type illustrated, they are opened by steam pressure from the steam chambers which they supply. The valve 33, for example, includes an operating stem 34 which is biased downwardly by a spring 30 to hold the valve closed against the steam pressure. The valve may be opened selectively by either a manually operable lever 35 or through a connection 39 under the control of a foot pedal. As pointed out in the above application, depressing of hand lever 35 lifts the left hand end of link 36 against the action of spring 30, to disengage it from the operating stem 34, permitting the steam to open the valve.

When the lever 35 is released, the biasing spring 30 closes the valve. When lever 39 is pulled, the right hand end of link 36 is lifted through lever 41 in response to the operation of the foot pedal to open the valve. As shown in Fig. 1, the hand operated lever 35 is associated with the handle 27 of the head, providing for convenient finger-tip control of the steam valve for the head. The operating lever 39 for the valve 33 is connected by a rod 42 to a bent lever 43 pivoted at 44. The lever 43 also carries an arm 45 connected through rod 46 to a bellcrank lever 47 pivoted at 48. One arm of the lever 47 is likewise connected by a rod 49 to an arm 51 attached to a collar 52 which is freely rotatable about a shaft 53. This collar 52 carries a lug 54 adapted for cooperation with lug 55 on a pivoted selecting lever 56 carried by a collar 57, also freely rotatable about the shaft 53. Collar 57 carries a lug 58 connected by a biasing or toggle spring 59 to a similar lug 61 on the selecting lever 56. Selecting lever 56 is pivoted at 62 and may be swung to either of two positions as shown in Fig. 2, and is held there by the toggle spring 59.

In its right-hand or dotted line position, lug 55 engages lug 54 so that actuation of collar 57 will cause the two collars 57 and 52 to move together to operate the valve 33. Rotation of collar 57 is brought about through a rod 63 pivotally connected to an arm 64 on the collar 57. Rod 63 is connected to a foot pedal 65 which is biased upwardly, that is in a valve closing direction, by a spring 66. Similar bias is imposed upon the operating linkage of valve 33 by spring 67.

In its left-hand or full line position of Fig. 2, lug 68 of selecting lever 56 passes into operative engagement with a lug 69 carried on a sleeve 71 which is rotatable with the shaft 53, and is held thereon by means such as a set screw 72. A coil spring 73 attached to a member 74 secured on shaft 53 is attached to the frame of the machine at 75 so as to bias the shaft 53 and the sleeve 71 to a predetermined position, in which valve operating arm 76 on member 74 occupies a position where the valve 29 controlling the steam spray to the buck 13 is closed.

As shown in Fig. 4, the arm 76 is slotted at 77 to receive the lower end of operating rod 31 of valve 29. This rod carries a stop nut 78 which is held in predetermined position by a lock nut 79. When lever 56 is in its full line position so that lugs 68 and 69 are engaged, downward movement of rod 63 by foot pedal 65 rotates

sleeve 71 and transmits this rotational movement to the shaft 53 and the arm 76 so as to release the pressure exerted by the arm against the stop nut 78 and permit the valve 29 to open by gravity and steam pressure. When the foot pedal 65 is released, it is restored to its normal position by spring 66 while the coil spring 73 rotates member 74 to restore the arm 76 to valve-closing position.

It will be clear that although the head steam valve 33 may be controlled in the usual manner through hand lever 35, it may also be operated at will by foot pedal 65 provided the lever 56 is in its dotted line position leaving both of the operator's hands free. Also that by moving the lever 56 to its full line position, the foot pedal 65 may be caused to operate the buck steam valve 29, thus providing for selective operation of valves 29 and 33 and for supplying spray steam from either the head or the buck by the same operating pedal. It requires nothing other than movement of the selecting lever 56 from one position to the other to effectuate a change in connection from the head to the buck or vice versa, and toggle spring 59 insures that the lever will always be moved to its full operative position in either direction.

In Fig. 1, operation of the head steam valve 33 is shown as being carried out through a system of rods and levers. The same result may be accomplished by the means shown in Fig. 5. In Fig. 5, the parts are similar to those of Fig. 1, except that the connection provided between the sleeve 52 carrying the lug 54 and the operating lever 39 of the steam valve 33 is effected through a Bowden wire 81. To provide for this operating connection, the collar 52a carries a downwardly depending arm 82 to which one end of the Bowden wire is connected. The casing for the Bowden wire is mounted in clamps 83 and 84 carried by the frame of the machine and the head carrying lever 15, respectively. The Bowden wire has its one end secured at 85 to the lever 39, and its other end to the lower end of lever 82. It will be obvious without further explanation that in the modification of Fig. 5, depressing of pedal 65 with the selecting lever 56 in its dotted line position, will open valve 33 and thus supply steam to the face of the head 17. Likewise that when the pedal 65 is released, spring 66 will restore the pedal to normal position. The valve 29 will, of course, be operated as in Fig. 1.

In the present disclosure the invention has been illustrated as applied to a well known type of press, but it is to be understood that the application of the inventive thought is not limited to the particular press shown. It may be applied to any garment pressing machine having relatively movable pressing members to which it is desired to supply steam spray during a pressing operation. It should also be pointed out that although two forms of head valve operating mechanism are disclosed, the invention is directed to the selective control of steam from either the head or the buck through a unitary means, regardless of the particular operating mechanism employed. Consequently, no other limitations than those expressed in the claims are to be implied.

What is claimed is:

1. In a garment press, a pair of relatively movable pressing members; steam spray means connected to both of said members; a spray control valve on each of said members and connected

to said spray means; and means comprising a single pedal for causing operation of either of said valves selectively, and a hand lever for connecting said pedal operatively to either of said valves to perform the selection.

2. In a garment press, a pair of relatively movable pressing members; a source of steam for both of said pressing members to effect a steam spraying operation; a control valve on each of said members and connected to said source; a foot pedal for operating either of said valves; and manually operable selecting means for connecting said foot pedal into operative relation with either of said valves.

3. A garment press comprising head and buck members; a source of steam connected to both of said members; a steam control valve on each of said members and connected to said source; means operated by a single pedal for actuating either of said valves; and hand operable means for performing a selection and operatively connecting said pedal operated means to either of said valves.

4. A garment press comprising relatively movable head and buck members; a source of steam connected to each of said members; a steam spray control valve on each of said members; a foot pedal; operating linkage for the head valve, said linkage including a system of links and levers; operating linkage for the buck valve; and a selecting lever for connecting said foot pedal to either of said linkages to operate either of said valves selectively.

5. A garment press comprising relatively movable head and buck members; a source of steam connected to each of said members; a steam spray control valve on each of said members; a foot pedal; a Bowden wire connection to the head valve; linkage for operating the buck valve; and a pivoted selecting lever for connecting said foot pedal into operative relation with either said

Bowden wire or said linkage to operate said valves selectively.

6. A garment press comprising relatively movable head and buck members; a source of steam for each of said members; a steam spray control valve on each of said members; a pivoted selecting lever mounted on the machine, said lever having two positions one for operating the valve of the head member and the other for operating the valve of the buck member; and a foot pedal connected to said lever and arranged to operate either of said valves.

7. A garment press comprising relatively movable head and buck members; a source of steam for each of said members; a steam spray control valve on each of said members; a selecting lever mounted on the machine, said lever having two positions one for operating the valve of the head member and the other for operating the valve of the buck member; a linkage between said lever and the valve on the buck member; a linkage system between said lever and the valve on the head member; and means operated by a single pedal for actuating one or the other of said valves depending upon the position of said selecting lever.

8. A garment press comprising relatively movable head and buck members; a source of steam for each of said members; a steam spray control valve on each of said members; a pivoted selecting lever mounted on the machine, said lever having two positions one for operating the valve of the head member and the other for operating the valve of the buck member; a linkage between said selecting lever and the valve on the buck member; a Bowden wire between the valve on the head member and said selecting lever; and means operated by a single pedal for actuating either said linkage or said Bowden wire, depending upon the position of the selecting lever.

WILLIAM STROBRIDGE.
